UNITED STATES PATENT OFFICE.

JOHN F. HOLLINGS, OF HARTFORD, CONNECTICUT.

FIRE-POT LINING.

SPECIFICATION forming part of Letters Patent No. 658,546, dated September 25, 1900.

Application filed February 13, 1899. Serial No. 705,437. (No model.)

To all whom it may concern:

Be it known that I, JOHN F. HOLLINGS, a citizen of the United States of America, residing at Hartford, in the county of Hartford and 5 State of Connecticut, have invented a certain new and useful Improvement in Fire-Pot Linings, of which the following is a description, reference being had to the accompanying drawings, wherein—

- 10 Figure 1 is a view of a furnace embodying said improvement in central vertical section. Fig. 2 is a plan view of the parts shown in Fig. 1. Fig. 3 is an edge view, on an enlarged scale, of one of the supporting-staves described hereinafter. Fig. 4 is a back view of the stave shown in Fig. 3. Fig. 5 is an end view of the stave shown in Fig. 3. Fig. 6 is an edge view, on an enlarged scale, of one of the tying-staves described hereinafter. 15 Fig. 7 is a back view of the stave shown in Fig. 6. Fig. 8 is an end view of the stave shown in Fig. 6. Fig. 9 is an edge view, on an enlarged scale, of one of the closing-staves described hereinafter. Fig. 10 is a back view 20 of the staves shown in Fig. 9. Fig. 11 is an end view of the stave shown in Fig. 9. Fig. 12 is an enlarged perspective view showing three of the staves in the position which they 25 occupy when in place. Figs. 13 and 14 are enlarged perspective details of one of the tying-staves and one of the closing-staves, respectively.

This improvement is one specially applicable to furnaces such as are commonly used 30 for heating houses and other buildings, as well as to those which produce hot air, hot water, or steam.

In the accompanying drawings the letter *a* denotes the fire-pot of a furnace of the class 35 already indicated.

The letter *b* denotes the grate.

The letter *c* denotes certain projections, such as are ordinarily found in furnaces of common construction. In the case where the 40 improvement forming the subject-matter of this patent is readily removable from the fire-pot these parts *c* form the supports for the parts of the improvement yet to be described. In some furnaces there are other supports of 45 this character to be found in ordinary constructions, and it will be understood that they 50 can be made specially for the purpose in hand.

The apparatus shown and described herein is of the class that are made adaptable to furnaces already existing and in ordinary use. 55

The letter *d* denotes a flexible band of sheet metal with ends that interlock by a motion lateral to the breadth of the band. It is made of such flexible material in order that it may be introduced through the door of the furnace and then put in proper place and shape. It is best that it should fit snugly against the wall of the fire-pot; but in some cases, in order to avoid the necessity of having a great number of sizes of this flexible band, spurs 60 or projections *d'* are provided thereon, which in the act of fitting the band in place may be turned out from the band laterally as far as necessary at different points and serve as points of contact with the wall of the fire-pot. 65 Whatever space there may be between the band *d* and the inner wall of the fire-pot is to be filled with suitable cement or the like. The letter *d* denotes parts of this flexible band, preferably at its upper edge, which are turned 70 inwardly to serve as a seat for the ring, next to be described.

The letter *e* denotes a ring made in interlocking sections—that is, interlocking at the ends, as by dovetails, as at *E*—a construction which permits the parts of the ring to be introduced through the door of the fire-pot and assembled within. 80

The letters *A B C* denote staves, which when assembled form an inner wall somewhat removed from the wall of the fire-pot and leaving an air-space between them. 85

The letter *f* denotes a ring the same in construction as the ring *e*, it also being made in interlocking sections. 90

The letter *g* denotes an apron lying partly upon the ring *f* and partly upon the floor of the door-opening into the fire-pot and serving practically as a continuation of that floor across the upper ring, and, if desired, there 95 may be aprons *h* for somewhat similar use at or near the rear.

Practically there may well be four of the staves *A*, which I will call the "supporting-staves," six of those lettered *B*, which I will 100 call the "tying-staves," and four of those lettered *C*, which I will call the "closing-staves," and all of these staves preferably have their edges struck on lines truly radial from the

center of the grate and their outer faces curved slightly, so as to fit within the circles formed by vertical rims e' and f' , projecting toward each other, respectively, from the 5 rings e and f , the staves being of sufficient length to reach across both rings, as seen. Through each ring and its rim is cut a dovetailed mortise, all the mortises being opposite each other, and in Fig. 2 I have illustrated four such mortises (lettered f^2) in the 10 upper ring, those in the lower ring being directly beneath and out of sight. Each supporting-stave A has on its back or outer face a longitudinal web A^4 , provided at its 15 extremities with outwardly-facing hooks A' , as best seen in Fig. 3, and at its lower end this stave also has the flange A^2 . Each tying-stave B has a similar web B^4 , with hooks B' and flanges B^2 at both ends. Each closing- 20 stave C has a similar web C^4 , except that it extends completely to the ends of the stave, and at its extremities this web is provided with dovetailed tenons C' . On the outer face of this web, near its lower extremity, is a stop 25 C^2 , facing toward the lower end of the stave and positioned to correspond with the tips of the hooks on the staves A and B, and the tenon C' at the upper end is extended downward to a point corresponding with the 30 throats of the uppermost hooks on the remaining staves, below which the sides of this tenon are cut out, as at C^3 .

In assembling the parts of this improved device the band d , if it is employed, is first 35 put in position, and the sections of the lower ring e are then inserted, interlocked at their ends, and supported by the seats d^2 of the band. The upper ring f is then put into place in like manner, and the operator is 40 ready to insert the stave. It is obvious that each of the supporting-staves A and the tying-staves B may be brought into position opposite one pair of mortises, then moved radially outward, so that the hooks pass into 45 these mortises, and then carried annularly around, so that the hooks take over the rims of the two rings. During this operation the flanges A^2 at the lower ends of the supporting-staves pass in under the lower fringe e , 50 as seen at the left of Fig. 1, and the flanges B^2 at both ends of the tying-staves B pass outside the rings e and f , as seen at the center of this view. Hence the staves A serve to support the upper ring, which might be lifted 55 off of them if it were not for the staves B, whose flanges B^2 tie the upper and lower rings e and f together. By preference two of the tying-staves B are brought into position across the interlocking ends of the sections of the rings, as seen at the right and 60 left of Fig. 2, so as to hold their dovetails E from disengagement. The complete device is built up by finally inserting the four closing-staves C at the points indicated in Fig. 2. 65 In this operation each of such closing-staves is brought into its proper radial position, but

raised higher than the staves alongside and its upper extremity borne inward. This permits the lower tenon C' to pass over the rim e and drop into the mortise therein until the 70 stop C^2 strikes upon the upper face of the lower flange e outside said mortise. Before dropping the stave into position, however, the cut-out portion C^3 of the upper tenon C' is passed into the mortise f^2 in the upper 75 ring f , which permits the body of the stave to assume a vertical position, and then when it is dropped into place both tenons C' engage and fill the mortises in the two rings, and the body of the stave closes the opening 80 remaining between the other staves which have previously been put in place. As so constructed it is impossible for any of the staves to become accidentally displaced. In order to remove them, it is necessary to reverse the operation just described with respect to one of the closing-staves, after which the entire set can be moved around until any one is opposite a pair of mortises, and then it can be withdrawn, as will be clear. 85

I claim—

1. In a furnace fire-pot, in combination, a grate, a flexible band with interlocking ends supported from said fire-pot, a sectional ring supported on said band, staves interlocking 95 with the ring, and a top ring interlocking the said staves, all substantially as described and for the purposes set forth.

2. In a furnace fire-pot, in combination, a plurality of sectional rings having their sections interlocked by dovetailed joints, an upright rim at the inner edge of each ring, registering mortises in pairs being cut through said rings and rims, and a series of staves extending across the two rings and certain of 105 which have flanges at their ends, webs on their backs, and hooks at the extremities of the webs projecting toward the flanges and engaging over said rims, certain of said staves also standing across the joints between the 110 ring-sections, all parts being proportioned as and for the purpose set forth.

3. In a furnace fire-pot, in combination, a plurality of rings having upright rims at their inner edges provided with registering dovetailed mortises, a series of staves extending across within the rims and having webs on their outer faces, certain of the webs having outwardly-facing hooks at their extremities, and certain other of the staves having webs with dovetailed tenons at their extremities the lower of which has a stop deeper than the mortise and the upper of which is cut away at its sides at a point positioned below the throats of the hooks of the staves just 125 mentioned, all constructed and arranged as and for the purpose set forth.

4. In a furnace fire-pot, in combination, a plurality of rings having upright rims at their inner edges provided with registering dovetailed mortises, a series of staves extending across within the rims and having webs on 130

their outer faces, certain of the webs having outwardly-facing hooks at their extremities, certain of the staves having outwardly-projecting flanges at their ends in addition to 5 said webs and hooks, and certain other of the staves having webs with dovetailed tenons at their extremities the lower of which has a

stop deeper than the mortise and the upper of which is cut away, all constructed and arranged as and for the purpose set forth.
